The ornamental design for a low mount snorkel, as shown and described.

DESCRIPTION

FIG. 1 is a front, right perspective view of a low mount snorkel, showing my new design, and in a state of use.

FIG. 2 is a front, right perspective view thereof.

FIG. 3 is a front elevational view thereof.

FIG. 4 is a back elevational view thereof.

FIG. 5 is a top plan view thereof.

FIG. 6 is a bottom plan view thereof.

FIG. 7 is a right side elevational view thereof; and,

FIG. 8 is a left side elevational view thereof.

The broken lines illustrating a paneling in FIG. 1 depict environmental structure that form no part of the claimed design. The broken lines on the surface of the article illustrate portions of the low mount snorkel that form no part of the claimed design.
